[57] CLAIM

The ornamental design for an auto wash air dryer, as shown and described.

DESCRIPTION

FIG. 1 is a front perspective view of an auto wash air dryer showing our new design;

FIG. 2 is a fragmentary view of the nozzle assembly shown in FIG. 1;

FIG. 3 is a bottom plan view thereof;

FIG. 4 is a rear elevational view thereof; and,

FIG. 5 is a top plan view thereof.

The nozzle assembly is the same on the inside of each leg.

FIG. 1

FIG. 2

FIG. 3

FIG. 4

FIG. 5
